UNITED STATES PATENT OFFICE

WILLIAM ANDREW UTTZ, SR., OF LAKEWOOD, OHIO

DESIGN FOR A MOISTENER FOR STAMPS AND ADHESIVE PAPER

Application filed February 10, 1930. Serial No. 34,465. Term of patent 14 years.

To all whom it may concern:

Be it known that I, WILLIAM ANDREW UTTZ, Sr., a citizen of the United States, residing at Lakewood in the county of Cuyahoga and State of Ohio, have invented a new, original, and ornamental Design for Moistener for Stamps and Adhesive Paper, of which the following is a specification, reference being had to the accompanying drawing, forming part thereof.

In the drawings Fig. 1 is a perspective taken from the front of the design showing the top front end and one side thereof; Fig. 2 is a perspective taken from the rear of the design, showing the rear end top and the other side thereof.

I claim

The ornamental design for a moistener for stamps and adhesive paper, as shown.

In testimony whereof I affix my signature.

WILLIAM ANDREW UTTZ, SR.
